UNITED STATES PATENT OFFICE.

NATHAN WISE, OF NEW YORK, N. Y.

ELECTRICAL MASSAGE INSTRUMENT.

1,123,639.

Specification of Letters Patent.

Patented Jan. 5, 1915.

Application filed June 21, 1911. Serial No. 634,541.

To all whom it may concern:

Be it known that I, NATHAN WISE, a citizen of the United States, residing in the borough of Manhattan, New York city, in the county of New York and State of New York, have invented certain new and useful Improvements in Electrical Massage Instruments, of which the following is a specification, reference being had therein to 10 the accompanying drawings, forming part thereof.

My invention relates to electrical massage instruments, and has for an object to provide a simple, durable, reliable and inexpensive instrument which will be convenient to manipulate and effective in operation.

More specifically an object of my invention is to provide an instrument of this class 20 which employs as a motor the simple and inexpensive solenoid and reciprocating core, and in which the pressure of the applicator against the part to be treated cannot impede the operation of the motor.

Another object is to provide an instrument in which the applicator may be so connected as to produce either a pounding or a rubbing movement on the part being treated, and in which the applicator will be 30 securely held when connected for either movement.

Another object is to provide for a maximum magnetic effect on the reciprocating core.

Another object is to provide an improved manually operative controlling switch.

My invention has still other objects and advantages and includes various arrangements and combinations of parts as will 40 hereinafter appear.

I shall now describe my invention with reference to the accompanying drawings and shall thereafter point out my invention in claims.

Figure 1 is a plan view of a complete instrument embodying my invention, with the top cap removed and the handle partly in section. Fig. 2 is a central vertical section of the same, with the handle in elevation.

In the illustrated embodiment of my invention, I employ an electric motor consisting of a solenoid 1, a reciprocative core

2, a circuit breaker operated by the reciprocation of the core, and retractile means 55 normally holding the core in retracted position. The solenoid 1 is wound on a spool composed of a suitable insulative material, such as fiber, and consisting of annular top and bottom plates 3 and 4, respectively, 60 and a hollow cylindrical sleeve member 5, projecting some distance above the top plate 3, as shown.

Inclosing the solenoid 1 is a casing consisting of a cylindrical body portion 6, a 65 top annular plate 7 fitting over the upper end of the sleeve member 5, and a bottom plate 8, the plates being secured to the cylindrical body portion by screws. This casing is composed of magnetic material, such 70 as soft iron, and serves to define the path for the magnetic flux of the solenoid 1 with a resultant increase in the magnetic effect on the core 2. To further augment this magnetic pull, an upwardly projecting hollow plug 9 of magnetic material is inserted in the center of the bottom plate 8 of the casing and extends up into the bottom of the insulative sleeve member 5 in proximity to the lower end of the core 2 where it produces a direct magnetic pull on the core; and to increase the magnetic surface the upper end of the magnetic plug member 9 may be made cone shaped and the adjacent 75 end of the core may be concaved to a corresponding shape, as shown.

From the center of the lower end of the core 2 in alinement with the core extends a rod 10 of relatively small diameter which slides in the bore in the hollow plug 9 and 80 serves as a hammer, as will hereinafter appear. This hammer member 10 is of such length that in the attracted position of the core the end of the hammer projects out of the lower end of the hollow magnetic plug 9, and in the retracted position of the core it is withdrawn into the plug.

To retract the core 2, a coiled thrust spring 11 is employed which surrounds the upper end of the core and bears at its lower 100 end on the top of the upper plate 7 of the casing, and bears at its upper end against the under side of an annular flange at the upper end of the core. It is apparent that when the solenoid is energized the core will 105 be attracted and drawn down into the sleeve

5 against the tension of the spring 11, and that when the solenoid is deenergized the core will be retracted by the spring 11. To cause the core to be thus rapidly reciprocated when the instrument is connected to a source of electrical energy, a make-and-break contact device is employed controlled by the reciprocation of the core, and this device will now be described.

10 On the top plate 7 of the casing is secured a contact-supporting plate 12 having an elevated central portion carrying a longitudinally adjustable contact screw 13 in alignment with the core 2. This contact screw is 15 insulated from the plate 12 and is connected to an insulated terminal 14 of the solenoid 1, which terminal extends up through an opening in the plate 7 and is attached to the screw 13 by a binding post nut 15 in the 20 usual way. The core 2 is provided in its upper end with a normally extended yieldable contact rod 16 in position to engage the lower end of the contact screw 13. A coiled thrust spring 17 is seated in a bore 25 in the upper end of the core 2 and bears at its upper end against an annular flange on the contact rod 16 and tends to hold the rod to extended position while permitting it to yield. The contact rod 16 slides in 30 the bore of a hollow removable plug 18 in the end of the bore in the core 2, and the flange on the rod 16 abuts against the lower end of the plug 18, the flange thus serving as a stop to limit the outward movement 35 of the rod under the pressure of the spring 17. Due to the engagement between the plug 18 and the flange, the rod is positively moved away from its complementary contact screw 13 when the core 2 is moved 40 downward, and the rod is always held steady and prevented from wabbling because of its long bearing. It will be apparent that the core, in its retracted movement, will be permitted to move after contact is made with the screw 13, and thus 45 contact is always assured while the core is allowed a considerable range of movement in order to deliver a relatively hard blow on the applicator, as will be described hereinafter.

The instrument has a hollow handle 19 through which enter the two leads, insulated from each other in the usual way. One lead 20 is connected directly to the opposite 55 terminal of the solenoid 1, and the other lead 21 is connected through a manually operative switch to the metal ferrule 22 of the handle, which is in electrical contact with the metal casing and is thus included in the 60 electrical circuit. The bore in the hollow handles is of larger diameter at the shank end of the handle and at the inner end of this enlarged bore is inserted a metallic ring 65 23, preferably of copper, to which the lead 21 is connected. On the side of the handle,

in position to be engaged by the thumb of the operator, is a sliding switch button 24 having a shank which is slideable in a slot 25 in the handle. The switch button 24 carries at the inner end of its shank a contact strip 26 which is of sufficient width at its point of attachment to the shank of the button to bear against the handle at each side of the slot and which has a front resilient portion extending outward into continuous 75 sliding engagement with the ferrule 22 (thereby providing sufficient friction to hold the switch in the position to which it is moved) and has a rear end resilient portion extending into position to engage the ring 80 23 when the switch is drawn back to connected position, as shown in the drawings, and is of such length that in the forward position of the switch its contact with the ring 23 is broken. This switch is very convenient for operation and since it has no bias to either position, the operator does not need to hold it under continuous control during the operation of the instrument. It is evident that when the switch is moved to 90 the connected position shown, the circuit through the solenoid will be completed as follows: through the lead 20, the solenoid 1, terminal 14, contact screw 13, contact rod 16, plug 18 and spring 17 to core 2, spring 95 11, casing top plate 7, cylindrical casing 6, ferrule 22, contact strip 26, ring 23, and lead 21 to the source of electrical energy. The core 16 is immediately attracted and a hammer blow is delivered on the applicator, but this breaks the circuit of the solenoid between the contact screw 13 and contact rod 16 and the attractive force on the core is terminated and the retractile spring 11 retracts the core, again completing the 100 circuit, and this operation is repeated with great rapidity and the core is thus rapidly reciprocated.

A usual applicator 27 is provided with a screw-threaded stem 28 for attachment to an applicator spindle 29, which is arranged in alignment with the core 2, and is slideable longitudinally in a sleeve 30. The spindle 29 has an enlarged flat head 32 on its upper and inner end, and a carrying-plate 34, of similar shape to the contact-supporting plate 12, is attached to the bottom plate 8 and surrounds the sleeve 30 underneath a shoulder on the sleeve, and serves as a guide for the head 32. A coiled thrust spring 33 surrounds the spindle 29 and the sleeve 30, and bears at its lower end on the plate 34 and at its upper end against the bottom of the spindle head 32, and tends to hold the spindle with the head against the bottom plate 8 and in front of the bore in the magnetic plug in the path of the hammer 10. Since, as previously stated, the hammer 10 in the retracted position of the core 2 is withdrawn into the plug 9 and the plate 8 115 120 125 130 135

serves as a stop to limit the upward movement of the spindle and prevents its contacting with the hammer 10 when the core is in retracted position, there is a clearance 5 in this position of the core between the end of the hammer 10 and the top of the spindle head 32, and, consequently, it will be manifest that the back pressure on the spindle 29 can never prevent the reciprocation of the 10 core and hammer, as would be the case if the spindle could follow the hammer back to the full length of its stroke. The operator may, therefore, press the applicator as hard as he desires against the surface to be treated 15 and the continuous rain of blows on the inner end of the spindle will cause the applicator to produce a pounding effect on the surface when the applicator is inserted in the screw-threaded bore provided for it in 20 the outer end of the spindle, in the position shown in the drawings. In order to permit the applicator to be connected to the spindle at right angles to the position shown in the drawings when it is desired to produce a 25 rubbing or reciprocating movement of the applicator instead of a pounding movement on the surface being treated, the applicator is made removable and a stem-receiving bore is provided in the side of the spindle as 30 shown. It is apparent that the means described for attaching the applicator to the spindle provides a rigid connection in either position of the applicator, in contradistinction, for example, to constructions in which 35 the applicator is hinged to the spindle.

To assemble the parts on the bottom of the instrument, the sleeve 30 is inserted in its bore in the plate 34, the spring 33 is placed in position about the sleeve 30, the 40 spindle 29 is inserted in the sleeve 30 and the carrying plate 34 is then secured to the plate 8. These parts are covered by a removable cap 31, and the upper part of the instrument is also provided with a removable cap 35, the removal of which gives access to the working parts above the solenoid.

It is obvious that various modifications may be made in the construction shown and

above particularly described within the 50 principle and scope of my invention.

I claim:

1. A massage instrument comprising an applicator carried by a longitudinally rigid reciprocable spindle, a solenoid device for 55 impelling said spindle forward by rapidly repeated blows of the solenoid core upon the end of the rigid spindle, and means for returning the spindle to initial position after each impact of the core upon the same. 60

2. A massage instrument comprising an applicator carried by a longitudinally rigid reciprocable spindle, a solenoid device for impelling said spindle forward by rapidly repeated blows of the solenoid core upon the 65 end of the rigid spindle, means for returning the spindle to initial position after each impact of the core upon the same, and means for limiting the approach of the spindle to the core. 70

3. A massage instrument comprising a casing, a longitudinally rigid reciprocable spindle carried by the casing and bearing an applicator at its outer end, a solenoid device within the casing for giving repeated 75 blows by its core upon the end of said spindle, means for returning the spindle to initial position after each impact of the core thereon, and a stop for limiting the approach of the spindle to the core. 80

4. A massage instrument comprising a casing, a substantially inelastic sliding member carried by the casing and bearing an applicator at its outer end, a solenoid device, within the casing, having an inelastic 85 core for impelling said member forward by successive rapid blows, a stop preventing said member from moving rearward to the core when the latter is in retracted position, and a spring for returning said inelastic 90 member and applicator to initial position after each blow of said core.

In testimony whereof I have affixed my signature in presence of two witnesses.

NATHAN WISE.
